(57) **CLAIM**

The ornamental design for a mobile device user interface, as shown and described.

DESCRIPTION

FIG. 1 is a front view of a first embodiment of a mobile device user interface showing a first image;

FIG. 2 is a front view thereof showing the second image;

FIG. 3 is a front view thereof showing the third image;

FIG. 4 is a front view thereof showing the fourth image; and

FIG. 5 is a front view thereof showing the fifth image.

FIG. 6 is a front view of a second embodiment of a mobile device user interface showing a first image;

FIG. 7 is a front view thereof showing the second image;

FIG. 8 is a front view thereof showing the third image;

FIG. 9 is a front view thereof showing the fourth image; and

FIG. 10 is a front view thereof showing the fifth image.

FIG. 11 is a front view of a third embodiment of a mobile device user interface showing a first image;

FIG. 12 is a front view thereof showing the second image;

FIG. 13 is a front view thereof showing the third image;

FIG. 14 is a front view thereof showing the fourth image; and,

FIG. 15 is a front view thereof showing the fifth image.

The broken lines shown in the drawings of a display screen and a mobile device are for illustrative purposes only and form no part of the claimed design.

The appearance of the transitional image sequentially transitions between the images shown within the embodiments shown in FIGS. 1-5, FIGS. 6-10 and FIGS. 11-15. No ornamental aspects are associated with the process or period in which on image transitions to another image.
